(57) CLAIM

The ornamental design for a bag, as shown and described.

DESCRIPTION

FIG. 1 is a front perspective view of a bag showing my new design;

FIG. 2 is a front view thereof;

FIG. 3 is an opposite side front perspective view thereof;

FIG. 4 is a side view thereof; and,

FIG. 5 is an opposite side view thereof.

The even-length broken lines represent stitching that forms no part of the claimed design. The dash-dot broken lines immediately adjacent to the shaded area define the bounds of the claimed design and form no part thereof. The dash-dot broken lines within the shaded area represent a zipper pull and a seam and form no part of the claimed design. The broken lines depicting the remainder of the bag form no part of the claimed design.
